UNITED STATES PATENT OFFICE.

WARREN F. CLARK, OF CLEVELAND, OHIO, ASSIGNOR TO THE STEAM-ELECTRIC PRODUCTS COMPANY, OF CLEVELAND, OHIO, A CORPORATION OF OHIO.

GENERATOR UNIT.

1,375,365.

Specification of Letters Patent. Patented Apr. 19, 1921.

Application filed April 24, 1919. Serial No. 292,520.

To all whom it may concern:

Be it known that I, WARREN F. CLARK, a citizen of the United States, residing at Cleveland, in the county of Cuyahoga and 5 State of Ohio, have invented a certain new and useful Improvement in Generator Units, of which the following is a full, clear, and exact description.

The present invention relates to what may 10 be termed a hot-plate device, the purpose of the device being to provide a hot-plate adapted to receive and support material which is to be worked on and heated simultaneously, and further the invention provides a coöperating device by which the 15 material may be held or clamped in position on the hot-plate.

The invention further consists in details of construction as will appear more to advantage as the description proceeds.

Generally speaking the invention may be said to comprise the elements and the combination thereof set forth in the accompanying claims.

Reference should be had to the accompanying drawings, forming a part of this specification in which Figure 1 is a perspective view showing the complete apparatus; Fig. 2 is a top plan view of the hot-plate 30 and an assembled clamping device; Fig. 3 is a transverse section through the hot-plate structure; Fig. 4 is a transverse section through a modified form of the hot-plate structure; Fig. 5 is an elevation with portions in section showing a part of said apparatus; Fig. 6 is a sectional elevation of a portion of the clamping device; Fig. 7 is a 35 sectional view showing a detail of construction; Fig. 8 is a bottom plan view of the plate portion of the clamping device.

Referring to the drawings 1 designates the hot-plate proper. This hot-plate comprises a top portion 1^a with depending sides or skirts 1^b. The hot-plate is preferably 45 made of sheet metal, which is advantageous not only from the view point of providing a structure of less weight than where the hot-plate is of cast metal, but also the use of sheet metal enables the structure to be fabricated with walls which are much thinner than would be the case of a solid structure, which in turn enables the more-ready transfer of heat to the top portion of the table at which portion the heat is utilized.

50 Within the skirt portions 1^b to which ref-

erence has already been made there is a member 2 which conforms in general outline with the outline of the skirt portions 1^b. This member 2 has depending flanges 2^a which engage with the interior of the skirt 60 portions 1^b, preferably by welding. If it is desirable, and it usually is, a reinforcing bar, such as indicated at 3 may extend in contact with the flanges 2^a being secured thereto by welding or otherwise in order to 65 provide a stronger structure. The bar 3 may be utilized to secure the edges of a cover 3^a which cover is made of asbestos or similar material.

At substantially the central portion of 70 the member 2 there is a substantially round opening with depending flanges 2^b. Co-operating with the flanges 2^b and extending through the opening before mentioned, is a thimble 4. This thimble has one end there- 75 of closed, which closed end extends into contact with the portion 1^a of the hot plate. The interior walls of the thimble are in part threaded in order to engage with a threaded element through which steam may be supplied to the space between the top 1^a and the member 2.

The thimble 4 is provided with a plurality of holes at 4^a which communicate with the space between the part 1^a of the hot- 85 plate and the member 2, thereby permitting ready communication.

The plate 2 is formed with a plurality of stuck up portions 2^c. These portions are in the form of nipples which extend toward 90 the plate 1^a and into contact with the same, and at the points where the nipples are in contact with the plate 1^a, they are joined by means of a spot weld.

The thimble 4 is also welded to the top 1^a 95 of the hot-plate as well as being joined to the flanges 2^b by welding, so that as will be seen, the plate 1 being joined to the plate 2 at a plurality of points, is effectively prevented from becoming warped due to the 100 successively heating and cooling actions to which it may be subjected.

Another construction for the hot plate is shown in Fig. 4. There there are provided two members 6 and 7 which extend in sub- 105 stantially parallel relationship with each other, and conform in outline with the flanges 1^b of the hot plate. These plates 6 and 7 are provided with depressed portions such as indicated at 8 and at these depressed 11

portions the plates 6 and 7 contact with each other. At these contacting portions the plates are joined together in a suitable manner, as by rivets such as indicated at 9. It 5 will be understood that these plates 6 and 7 will be joined to each other at numerous points. The plate thus lies in substantial contact with the top 1^a of the top so as to be in best position to communicate the heat 10 to the top portion of the hot plate. Although not shown, it will be understood that a suitable inlet is provided to the space between the plates 6 and 7 of the same form as that shown in Fig. 3 or an equivalent 15 thereof.

The hot plate 1 may through the thimble 4 be connected with any suitable sort of heating fluid and in the drawing I have indicated a steam generating unit which is generally designated at 10. This heating unit has a threaded pipe portion 11 which communicates with the threads in the nipple 4. The type of steam generator to which reference has been made is the same as that 20 disclosed in my co-pending application Serial Number 292,519 filed April 24, 1919.

The hot plate which has thus been described when associated with a suitable heating fluid supplying device such as steam 30 generator 10, forms a hot plate which is adapted for very many purposes; in fact however the material worked upon is required to be kept in a heated condition during the working period.

35 The temperature at which the hot plate is maintained may of course be varied in accordance with the temperature at which it is desired to maintain the hot plate.

The hot plate construction is particularly 40 adapted to form a part of the vulcanizing apparatus, wherein, patches, sections or other repair work is to be effected upon tires, tubes or other rubber articles.

Such a usage as that which has just been 45 stated, requires the use of suitable clamping devices whereby the work may be clamped and held to the hot plate during the vulcanizing action.

The construction herein proposed provides 50 a plurality of adjustable clamping devices which are mounted adjacent to the hot plate and in a position for convenient use.

The hot plate is provided with a plurality of extending ears 12. In these ears is mounted 55 a longitudinally extending rod 13. Upon the rod there are mounted a plurality of clamping devices all of which are similar so that a description of one will suffice for all.

Upon the rod 13 there is mounted an arm 60 generally designated at 15. This arm at its lower portion is provided with a part 16 which is adapted to slide upon the rod 13 so that the bracket may be positioned longitudinally with respect to the hot plate 13.

65 The arm 15 is curved and has a portion such

as indicated at 17 which is adapted to lie substantially parallel with respect to the hot plate when the clamp is in its fastened position.

The arm 17 of the clamping device is provided with spaced parallel portions such as indicated at 18 and adjacent its forward portion the clamp is provided with a handle 19. Adjacent the handle 19 is a depending hook 20, this hook being adapted to engage beneath the edge of the hot plate so as to hold the clamping device in position when an article is being pressed beneath it. The hook 20 is provided with an extending flat portion 20^a which may be engaged by the hand 80 of the operator to move the hook 20 either into engagement or out of engagement with the hot plate, as may be desired.

The portion 18 of the arm 17 receives a block 21 which block is provided with 85 grooved side walls as indicated at 21^a, through which grooved portions the sides forming the portions 17 of the clamping device engage, so that the block 21 may be moved forward or backward in the portion 90 18 in a direction transverse with respect to the hot plate.

The block 21 has an interior opening which is threaded, and through this opening there extends a threaded stem 22. The 95 stem at this upper end is provided with a handwheel 23 by which the stem may be manipulated to adjust its position in the block 21. The stem 22 is hollow and through it there extends a rod 24. This rod at its 100 lower end is provided with a presser plate 25 having a substantially centrally arranged raised portion 26. The plate also has an opening 27 which is of sufficient size to permit the head 24^a to pass through it and there 105 is a groove 28 which communicates with an opening 29 at the center of the raised portion 26. The opening 29 is of sufficient size to receive the rod 24 but does not permit the 110 passage of the head 24^a.

The construction described is for the purpose of assembling plate 25 which may be conveniently done by inserting the head 24^a through the opening 27, moving the rod through the passageway 28 of the plate into 115 the circular opening 29.

A spring 30 encircles the rod bearing at one end upon the plate 25 and at its opposite end bearing against the cup shaped member 31, which cup shaped member is provided 120 with a central threaded opening which receives an extension 22^a upon the member 22; this construction being for the purpose of positioning cup 31.

It will be obvious that turning the handwheel 23 causes the stem 22 to move through the block 21 thereby to exert pressure upon the hot plate when the plate 25 is in contact therewith, but this pressure is a yielding pressure as the spring 30 is more or less com- 125 130

pressed by this action. Therefore the pressure is exerted through the action of the spring 30.

This is important particularly where the 5 device is used for an operation involving vulcanizing, as it permits a pressure of a uniform amount to be maintained upon the article during vulcanization for as the rubber flows during the vulcanizing period, the 10 spring maintains all the pressure.

From the foregoing description it will be seen that each clamp may be moved longitudinally with respect to the hot plate, while block 21 of each clamp may be moved 15 in a direction transverse with respect to the hot plate, thus enabling the plate 25 to have substantially universal adjustability with respect to the hot plate.

The clamp structure as a whole may be 20 moved to a position which does not obstruct the top of the plate as shown in the right hand portion of Fig. 1 and for this purpose the portion of the bracket which extends below the part 16 is provided with 25 an extension 16^a, which is so fashioned that when the bracket as a whole is moved upon the rod 16 as a pivot, the part 16^a will engage with the lower side of the hot plate. When the clamping device is moved 30 to a position, such that the center of gravity lies beyond the pivoting point, the device by its own weight remains in the position shown at the right hand portion of Fig. 1.

Where inner tubes or other flexible pieces 35 of rubber material are being vulcanized it is desirable to provide some means for supporting the same above the hot plate so that only these portions being treated are in contact with the hot plate. For this 40 purpose a rack such as indicated at 35 may be provided, the side members of the rack or support extending through suitable openings provided adjacent the ends of the rod 13 at which position the rack may be 45 cured.

It will be understood that where the device is used for vulcanizing, the portion 50 of the rubber article being vulcanized will be positioned beneath the pressure plate 25 and held in contact with the hot plate during the vulcanizing operation and it will be readily seen that whether the work 55 being performed is vulcanizing or not that the clamps are quickly adjusted to hold any article or piece of work into contact with the hot plate during the period it is being worked upon.

I claim:

1. In a device of the character described 60 a combination with a plate member, a rod mounted adjacent one side of the plate member, of a clamping device comprising an arm, one end of which is pivotally mounted upon such rod, capable of sliding 65 along the rod and a movable presser mem-

ber carried by the said arm and capable of moving upon the arm and transversely with respect to the hot plate.

2. In a device of the character described the combination with a plate member, a 70 rod mounted adjacent one side of the plate member, of a clamping device comprising an arm, one end of which is pivotally mounted upon such rod, capable of sliding along the rod and a movable presser mem- 75 ber carried by the said arm and capable of moving upon the arm and transversely with respect to the hot plate, a means for fastening the free end of the lever to the hot plate. 80

3. In a device of the character described the combination with the plate member of a clamping device comprising an arm which is pivotally mounted at one end at one side of the plate member a block slidably mounted in said arm a threaded rotatable member mounted in such block and a presser head associated with the said rotatable member. 85

4. In a device of the character described 90 the combination with a plate member of a clamping device comprising an arm which is pivotally mounted at one end, at one side of the plate member, a block slidably mounted in said arm, a threaded rotatable 95 member mounted in such block and the presser head associated with the said rotatable member, a hook member pivoted adjacent an end of said arm and bearing to engage to meet a portion of the said plate. 100

5. In a device of the character described the combination with a plate member of a clamping device comprising a lever one end of the said lever being pivoted adjacent a side of the plate, such lever having an extension beyond the pivotal point thereof, which is adapted to engage a portion of the plate when the clamping device is moved in one direction about its pivot, a block member slidably mounted in the said arm, a 105 rotatable member on said block, a presser head associated with the said rotatable member and the hook threadably mounted adjacent an end of the arm and adapted to engage with the portion of the said plate. 110

6. In a device of the character described the combination with a plate member a rod mounted adjacent one side of said plate member, of a clamping device comprising a lever, said lever at one end thereof being 115 mounted upon the said rod, and slidably upon the rod, a block slidably mounted upon said lever and a threaded rotatable member mounted in said block, a presser head associated with the said rotatable member, means associated with an end of the lever for holding the same with respect to the plate. 120

7. In a device of the character described, 125 the combination with a plate member of a 130

clamping device comprising an arm pivoted at one end thereof adjacent a side of the plate, a block slidably mounted upon the said arm, a threaded rotatable member extending through a threaded opening in the block, a presser head carried by said rotatable member, a spring co-operating with the said rotatable member, and bearing upon the said presser head, a plate carried by the 5 threaded rotatable member against which the opposite end of the spring engages, means for holding the free end of the lever with respect to the said plate.

8. In a device of the character described, 10 15 the combination with a hot plate comprising an outer member which has a substantially flat surface and with depending flanges at its edges, the flanges of said inner member lying within and in engagement with the flanges on the outer member, there 20 being a space between the inner and outer member to provide a chamber, an annular member extending through the inner member and forming an opening to the space before mentioned.

9. In a device of the character described 25 the combination with a hot plate comprising an outer member, an inner member secured to the outer member and forming a space between said members means for spacing the said members apart said inner member being provided with a fluid entrance opening.

10. In a device of the character described 30 35 the combination with a hot plate comprising an outer member, an inner member secured to the outer member providing the space between the said members said inner member having struck up portions which engage with the inner surface of the outer member, thereby spacing them apart the inner member being provided with a fluid entrance opening.

11. In a device of the character described 40 45 the combination with a hot plate comprising an outer member, an inner member secured to the outer member, said inner member being provided with struck up nipples which engage with the inner surface of the outer member, said nipples being attached to the outer member, the inner member being provided with a fluid entrance opening.

12. In a device of the character described 50 55 the combination with a hot plate comprising an outer member, an inner member secured to the outer member, said inner member be-

ing provided with a plurality of struck up nipples, said nipples being secured to the outer member and said inner member having a central opening, and a thimble extending through the said opening and engaging with the inner surface of the outer member, said thimble being provided with openings which communicate with the spaces between the said members. 60 65

13. In a device of the character described the combination with a hot plate comprising an outer member having a substantially flat surface with depending flanges at its surface, an inner member which is secured to the outer member at the flanges thereof, means for spacing the said inner member with respect to the outer member the inner member being provided with a fluid entrance opening. 70 75

14. In a device of the character described the combination with a hot plate comprising an outer member having a substantially flat surface with depending flanges, an inner member secured to the outer member 80 at the flanges thereof, said inner member being provided with struck up nipple portions which nipple portions are secured to the outer member, the inner member being provided with an opening and a thimble extending through said opening said thimble member engaging with the inner side of the outer member, and being provided with openings communicating with the spaces between the said members. 85 90

15. In a device of the character described the combination with a hot plate comprising a pair of spaced plate members which are secured to each other at their edges, means for securing the said plate members with respect to each other at various points throughout their extent and a cover having portions which co-operate with the said flanges of the plates. 95

16. In a device of the character described 100 the combination with a hot plate comprising a pair of spaced plate members which are secured to each other at their edges, each of the said plates being formed with oppositely disclosed depressed portions the said depressed portions of the plate engaging with each other and being secured with each other, a cover member having portions which co-operate with the said flanges of the plates. 105

In testimony whereof, I hereunto affix my 110 signature.

WARREN F. CLARK.
